UNITED STATES PATENT OFFICE.

RAYMOND SKULINA, OF CHICAGO, ILLINOIS.

INCLINOMETER.

1,297,504.

Specification of Letters Patent. Patented Mar. 18, 1919.

Application filed January 29, 1918. Serial No. 214,378.

To all whom it may concern:

Be it known that I, RAYMOND SKULINA, a subject of the Emperor of Austria-Hungary, residing at Chicago, in the county of Cook 5 and State of Illinois, U. S. A., have invented new and useful Improvements in Inclinometers, of which the following is a specification.

This invention relates to a device in the 10 nature of an instrument particularly adapted for use on aeroplanes and the like.

It is among the objects of my invention to provide a device which will indicate to the aviator whether he is flying parallel to the 15 surface of the earth or at any inclination thereto, and thereby enable him to maintain his craft in flight at any definite distance above the earth that may be desired. A further object of my invention is to provide 20 such a device which, in addition to being simple in construction and comprising but a few parts, will be sensitive enough to respond instantly to any inclination that the craft may assume, and thereby permit the 25 aviator to maintain his craft in its flight at a desired distance above the surface of the earth. Furthermore, my device is so constructed that, should the aviator be at a considerable distance above the earth and 30 fly into a cloud bank, he will be enabled to determine from my device whether he is flying right-side-up or upside-down.

The invention consists further in the matters hereinafter described and more particularly pointed out in the appended claims.

In the accompanying drawings—

Figure 1 is a view of a device constructed in accordance with my invention and being shown partly in section and partly in elevation and in the position it occupies when mounted on the instrument-board or panel of an air craft or the like;

Fig. 2 is a top plan view of the parts shown in Fig. 1;

Fig. 3 is a vertical sectional view of a detail of construction, taken on line 3— of Fig. 2; and

Fig. 4 is a vertical sectional view of a detail of construction, taken on line 4— of Fig. 2.

As shown in the drawings, the device embodying the features of my invention comprises a casing 10, made in two parts 11 and 12, which when clamped or otherwise secured together form a hollow casing for housing within the same the operative parts

of my device. Said casing 10 is preferably made spherical in form, as illustrated in Fig. 1, with the lower part 11 made of metal or other suitable material, and the upper part 12 made of transparent glass or the like, so that a view may be had at all times into the casing from the outside thereof for the purpose of noting the position of the index arm or pointer, to be hereinafter referred to. The parts 11 and 12 are preferably secured together by an annular clamping ring or member 13 having screw-threaded connection with the lower part 11 and being provided with an inwardly extending annular flange 14, adapted to engage above an outwardly extending annular rib or bead 15 on the upper part 12. To prevent the glass cover or upper part 12 from being fractured when drawn against the lower part 11 by the clamping ring 13, I interpose a rubber or like yieldable gasket 16 between the opposed annular edges of such parts, as shown in Figs. 1 and 3. In order to enable my device to be readily mounted on and be secured to an instrument-board of an air craft or the like, I provide the lower part 11 of the casing with an outwardly extending annular flange 17, provided with a plurality of suitably spaced bolt holes 18 extending therethrough. In Fig. 1, 19 designates an instrument-board on the kind of craft referred to, and, as shown, said board is provided with a hole or opening 20 of a size to receive the lower part 11 of the casing 10. Said flange 17 seats against the board 19, and is secured thereto by a plurality of bolts 21 inserted through said bolt holes 18 and registering holes provided for that purpose in said board. With the casing in such position, it follows that the glass cover 12 is located on the outside of the board and in position to be viewed by the aviator like any other instrument that may be applied to said board.

Located within said casing is a member 22, preferably given the shape of an open frame, as shown in the drawings, and arranged to extend horizontally across the casing and pivoted at its ends thereto on horizontally arranged pivot pins or trunnions 23, to be hereinafter referred to in detail. Said frame member 22 has a width less than its length and is preferably made so as to have its widest part at the center, and within said frame is located a bar 24, the latter extending across the central portion of the

frame, as shown, and being pivotally mounted therein on suitable pivot pins or trunnions 25, to be presently referred to in detail. The frame 22 is pivotally mounted so as to revolve or swing about an axis running lengthwise thereof, and the bar 24 is pivotally mounted so as to swing or rock about an axis running lengthwise of the bar but at right-angles to the axis of rotation of the frame, as indicated in Fig. 2. Depending from the center of the bar 24 is a rod 26 having at its lower end a weight 27. Extending upward from the center of the bar 24 is a rod 28 having at its outer end an index finger or pointer 29. The outer end of the rod 28 terminates closely adjacent the under side of the glass cover 12, and on the outer face of said cover I provide a number of scale lines 30, 31, 32, and 33. Such lines are usually etched in the outer surface of the glass cover 12 and extend clear across the same. The two lines 30, 31 intersect each other at the center of the spherical curvature given to the glass cover 12, and are arranged at right-angles to each other. The other two lines 32, 33 bisect the angles formed between the lines 30, 31, and are interrupted or broken adjacent the point of intersection of the lines 30, 31. When placing my device on the instrument-board 19, the same is so positioned that the scale line 30 is in a vertical plane extending lengthwise of the air craft, that is, from stem to stern, and it follows that the other scale line 31 will be in a vertical plane extending transversely across the craft and at right-angles to the first mentioned vertical plane. Each scale line 30, 31 may be provided with a number of scale marks 34, properly spaced apart so as to indicate the degree of inclination assumed by the air craft. By making the index finger or pointer 29 cross-shaped, as shown, the same will coincide with both of the scale lines 30 and 31, when said pointer is at the intersection of such lines, and thereby serve to indicate that the air craft is traveling at the desired level above the surface of the earth. That portion of the rod 28 where it is secured to the bar 24 is in alignment with the depending rod 26 and, in effect, a continuation thereof. As is the customary practice, the instrument-board 19 is arranged at an inclination, so as to be directly in front of the aviator when he occupies his seat in the air craft and thus enable him to have a ready view of all of the instruments that may be mounted on the board, without being required to leave his seat or lean over the board to be directly above it, as would be the case should the board be arranged flat like a table top. When the casing 10 is mounted on said board, the point of intersection of the scale lines 30, 31 is directly in front of the aviator, as is apparent. The weight 27 is heavy

enough to overbalance at all times the combined weight of the upper arm 28 and its pointer 29 and thus maintain said rod 28 constantly above the frame 22. Moreover, the weight 27, being below the frame and being acted upon by gravity at all times, maintains the rod 26 always in a relatively fixed vertical position and, likewise, the rod 28 and its pointer or indicating finger 29 in a relatively fixed and immovable position, regardless of the degree of inclination given to the casing 10 and board by the air craft in its flight. With the board 19 arranged at the inclination shown, the pointer 29 would not coincide with the scale lines 30, 31 at 70 their point of intersection while the air craft is traveling parallel to the surface of the earth, should all portions of the upper rod 28 extend vertically upward and in alignment with the lower rod 26. In order 75 to cause the pointer 29 to coincide or register with the lines 30, 31 at their point of intersection under the conditions just noted, I find it necessary to bend or offset the upper rod 28 toward the aviator and in a vertical 80 plane of the scale line 30 to an extent sufficient to cause the pointer 29 to coincide with said scale lines 30, 31, when the craft is flying parallel to the earth's surface. 85

The device shown and described, when in 90 use, operates in the following manner. The frame member 22, being pivoted at its ends in the casing 10 on horizontally arranged pivot pins 23, 23, permits the casing 10 to be tilted or moved relatively to said frame member in a vertical plane containing the scale line 30, while the weight 27, due to the action of gravity thereon, serves to hold the frame member immovable and in the horizontal position shown in Fig. 1. The cross-bar, being pivotally mounted at its ends in the frame member 22 on an axis transverse to the pivotal axis of the latter, permits the casing 10 to be moved or tilted laterally or in a vertical plane containing the transverse 100 scale line 31, while the weight 27 holds the bar 24 immovable and in the horizontal position shown in Fig. 1. The action of gravity on the weight is the same in the latter case as in the former. The result is that, 105 should the aeroplane tilt downward, the casing 10 would be tilted likewise, and the pointer 29, being held immovable by the weight, would register on the scale line 30 the degree of downward inclination thus assumed by the aeroplane. That is, the pointer would indicate on that portion of the scale line 30 below the transverse scale line 31, this being due to the fact that the pointer 29 is held in a fixed position by the weight, while 110 the glass cover 12 moves with respect thereto in the direction noted. Should the aeroplane tilt upward, as when ascending, the pointer 29 would likewise indicate the degree of upward inclination assumed by the 115 aeroplane. 120

125

craft by registering on that portion of the scale line 30 above the transverse scale line 31, as is apparent. The diagonally arranged scale lines 32 and 33 are provided for the purpose of enabling the aviator to determine whenever the aeroplane should tilt vertically and laterally, and thus permit him to at once rectify his direction of flight, should he desire to maintain his craft at a constant level above the surface of the earth.

Aviators have experienced the difficulty heretofore of being unable to maintain their crafts at a required level at all times above the ground, owing to the fact that they fly at high altitudes and have no surrounding objects by which to determine whether they are flying at all times at a certain distance above the ground. It is due to this also that aviators when flying at high altitudes are unable to detect instantly when their air crafts are traveling at an inclination downward or upward. Furthermore, when flying at high rates of speed in cloud banks or fogs at high altitudes, the aviator is sometimes unable to determine whether he is flying right-side-up or upside-down. With my device it is apparent that these various difficulties may be readily overcome, and the aviator may maintain the flight of his air craft above the ground at any desired height that he may wish to assume and maintain his flight at such distance as long as required, because the pointer 29 will indicate on the scale lines of the glass cover any changes of inclination that may be assumed by the air craft, and thus permit the aviator to rectify the same. Moreover, with my device, should the aviator's view be obstructed from the earth and thus cause him to lose track of directions up and down, so as to make it possible for him to fly up-side-down and not be aware of it, my device will indicate such fact immediately, because then the weight 27 will be in a position adjacent the glass cover, while the pointer 29 will take a position within the opaque part 11 of the casing 10.

Other and further advantages of my device will be readily apparent to those skilled in the art to which it appertains.

In Fig. 3 I have shown in detail one way in which I may make the pivotal mounting for the frame member 22. As shown, I provide a recess 35 in the lower part 11 of the casing and insert through the inner wall of such recess the pivot pin 23, which is in the form of a set screw having its inner end pointed and engaging in the end of the frame member 22. To hold the set screw in the proper position, I provide the same on the inside of the casing with a jam-nut 36. One preferred way in which to pivotally mount the bar 24 is shown in detail in Fig. 4, wherein I provide the two pivot pins 25, 25, in the form of set screws one at each end of the bar. Each set screw has a pointed end

adapted to engage the associated end of the bar, as shown, and to hold such screws in position against rotation I provide each with a jam-nut 37. Furthermore, said Fig. 4 shows one way in which the arms 26 and 28 may be secured to the bar 24, and, as illustrated, each arm is independent of the other and threaded into the bar and held from rotation by suitable jam-nuts 38, 39 provided on the bars for that purpose.

Although I have shown and described in detail a device embodying the features of my invention, yet it is to be of course understood that the details of construction and arrangement of parts illustrated may be variously changed and modified without departing from the spirit and scope of my invention, and I do not wish to be limited to the exact details of construction and arrangement of parts shown, except as pointed out in the appended claims.

I claim as my invention:

1. A device of the character described, comprising a casing having a transparent cover with a scale thereon, an open frame member pivoted in said casing at diametrically opposed points and having a width less than its length, a bar extending transversely across the opening in said frame member and pivoted at its ends thereto, the pivotal axis of said bar being at right-angles to that of the frame, a rod projecting upward from said bar and provided with a pointer for said scale, and a weighted member depending from said bar.

2. A device of the character described, comprising a casing having a transparent cover with intersecting scale lines thereon, a pointer having cross-arms adapted to register with said scale lines at the place of intersection thereof, and means for connecting said pointer with said casing so that the latter may have movement relatively to said pointer and means for holding said pointer in a relatively fixed position during any movement of said casing with respect to said pointer.

3. A device of the character described, comprising a casing having a transparent cover with intersecting scale lines thereon, a member pivoted in said casing at diametrically opposed points, a bar arranged transversely to said member and being pivoted thereto, a rod projecting upward from said bar and being provided at its upper end with cross-arms adapted to register with said scale lines at the point of intersection thereof, and a weighted member depending from said bar.

4. A device of the character described, comprising a casing having a transparent cover provided with a scale thereon, a normally horizontally arranged member pivotally mounted in said casing, a weighted member depending from said member, and a rod

secured to said member and extending upwardly therefrom toward said cover and having at its outer end a pointer located beneath said scale, and the outer portion of 5 said rod being bent in the direction of one of the scale lines on said cover.

5. The combination with an inclined instrument-board, of a casing mounted thereon and having a transparent cover with intersecting scale lines thereon, a member located 10 in said casing and being pivotally connected thereto at diametrically opposed points, a bar arranged transverse to said member and being pivoted at its ends thereto, a rod projecting upwardly from said bar and provided with a pointer for said scale, and a 15

weighted member depending from said 5, said rod having its upper portion bent in the direction of one of said scale lines and the point of intersection of said scale lines being in a plane at right-angles to said board and passing through the pivotal axis of said member. 20

In testimony that I claim the foregoing as my invention, I affix my signature in the 25 presence of two witnesses, this 19th day of January, 1918.

RAYMOND SKULINA.
